UNITED STATES PATENT OFFICE.

ARTHUR A. JOHNSON, OF NEW YORK, N. Y., ASSIGNOR TO THE EGRY REGISTER COMPANY, OF DAYTON, OHIO.

AUTOGRAPHIC REGISTER.

Application filed November 16, 1922. Serial No. 601,204.

To all whom it may concern:

Be it known that I, ARTHUR A. JOHNSON, a citizen of the United States, residing at New York city, in the county of Bronx and State of New York, have invented certain new and useful Improvements in Autographic Registers, of which the following is a specification, reference being had therein to the accompanying drawing.

10 This invention relates to autographic registers and the like and in certain of its aspects particularly relates to registers of the pin-wheel type.

It is my object to provide a machine which 15 will furnish the positive aligning characteristics of a pin wheel feed and the advantages of the ejecting by pin wheels with the advantages of a pull-out type of autographic register.

20 It is a further object to provide in such a combination a register in which the advance may be made step by step to disclose additional writing spaces, and still maintain constantly the alignment of the 25 several sheets of paper in forward and lateral directions.

It is a further object to provide an unwinding means for the sheets of paper which will not impart the strain on the 30 paper at the point of its contact with the pins of the pin wheels which is now characteristic of pin wheel machines when the paper is both unwound and ejected at the same time by the same agency.

35 A feature of this invention is the provision of a pin-wheel type of register in which the feeding of the webs passing through the machine is effected by a simple push or pull movement of an operating part, or 40 both, as distinguished from a solely rotary movement thereof. Ordinarily, registers of the pin-wheel type are operated by the rotation of a crank; but, according to this invention, the feeding is effected by, or is 45 a consequence of a longitudinal movement of the pin-wheels. In some embodiments of this invention the longitudinal movement of the pin-wheel is accompanied by a rotating feeding movement, while in other cases the webs are fed by the pins of the wheels without rotation of the latter.

50 A further feature of this invention is the

provision of means and the arrangement of parts whereby the webs are fed from their supply rolls at such times as the pin-wheels 55 are not rotating, and irrespective of the rotation of the pin-wheels. This has the effect of enabling the webs to move over the pin-wheels without liability of tearing and of permitting the parts to be made less accurately, thus reducing costs of production.

Another feature of this invention is the provision of a register which, without decreasing the hand-rest space and without necessitating the use of short forms, may 60 be made substantially shorter than ordinary registers having the same capacity for supply rolls of paper. This is accomplished, in some forms of the invention, by the provision of a writing opening or zone which 65 is preferably about one-half the length of the "form", and by providing for the feeding of the normally concealed half of the "form" to the writing zone by a simple operation. The necessity of feeding the webs 70 during the writing or "filling-out" of a form is not objectionable because as a general rule most of the "forms" are only half filled by items, the surplus being provided merely for the purpose of enabling unusually 75 large numbers of items to be written.

In this form of the invention, the entire second half of the "form" may be fed or moved to the writing zone by a single operation or by means of auxiliary mechanism 80 for feeding the webs a line at a time. This line space mechanism may operate independently of the pin-wheel or other feeding mechanism.

As above stated the feeding of the webs, 85 according to the present invention, is incidental to a traveling movement of the pin-wheels. For this purpose, the pin-wheels are mounted on a carriage to move to and fro on the main frame of the register. In 90 some forms of this invention, this carriage also embraces the platen for supporting the webs during the writing operation. In other forms, however, the platen is independently supported.

100 Other features and advantages will hereafter appear.

In the accompanying drawings:

Figure 1 is a side elevation partly in sec-

tion of one form of the invention showing the parts in normal position for writing the first half of a "form".

Figure 2 is a fragmentary plan view 5 showing the parts in the position shown in Fig. 1.

Figure 3 is a front view of part of the feeding mechanism of the register shown in Fig. 1.

10 Figure 4 is a detail view showing one form of mechanism for feeding the webs line-by-line.

Figure 5 is a detail view showing a back check mechanism forming part of the feeding mechanism of this invention.

Figure 6 is a side view of the register shown in Fig. 1 with the parts extended to show the second half of a "form" in writing position.

20 Figure 7 is a plan view of the parts in the position shown in Fig. 6.

Figure 8 is a side view of another form of this invention.

Figure 9 is a front view showing part of 25 the feeding mechanism of the register shown in Fig. 8.

In the form of the invention shown in Figs. 1 to 7 inclusive, the frame of the machine comprises side plates 20 and a portion or hand rest 21 at the top formed integral therewith. The side plates 20 are provided with feet 22 forming the support for the register; and the front of the register is provided with a plate 23.

30 As in ordinary autographic registers, the work sheets are in the form of webs 26 of indefinite length which are wound on rolls 24 supported on spindles or rods 25 pivoted in the side plates 20 in any approved or suitable manner. The webs 26, which may be printed or ruled, ultimately pass under the hand rest 21 and over the platen 27, and while upon the platen are in position for use in the writing opening or zone 28 immediately in front of the hand rest 21. The webs are held in writing position by pins 29 of pin-wheel 30 which are mounted upon and are secured to a shaft 31 so as to rotate in unison. The pins 29 engage perforations 32 in the side margins of the webs and thus positively control the webs and cause the several superposed webs to feed in accurate unison without danger of them creeping relatively.

55 According to this invention, the feeding of the webs is accompanied by a longitudinal movement or travel of the pin-wheels. In this traveling movement of the pin-wheels, they may or may not, according to other structural features of the particular embodiment, be accompanied by the platen. In the embodiment of the invention shown in Figs. 1 to 7, in which only one-half of the "form" is exposed at the writing zone at one time, the platen 27 is

mounted to travel with the pin-wheels 30, and, for this purpose, the pin-wheel shaft 31 is mounted to rotate in a frame 33 comprising downwardly extending sides 34 and a top portion 35 formed integral with the 70 platen 27. At the rear of the platen 27 is provided with downwardly extending arms 32 carrying rollers 36 riding on rails 37 struck-up from the side plates 20 of the frame, and it is by means of these rollers 36 75 and the rails 37 that the rear of the platen is supported for traveling movement. The forward part of the platen and the pin-wheel frame 33 is supported at each side by means of a pinion 38 mounted on a stub 80 shaft 39 carried by the sides 34 and which ride upon a rack 40 secured to the side plates 20 of the frame. The racks 40 and the pinions 38 have other functions which will hereinafter be described, and, so far as 85 the supporting of the forward part of the platen is concerned could be replaced by simple rollers and rails.

As shown in the drawings, in this form of the invention there is only one-half of the "form" exposed in the writing zone at one time, and this has the advantage that the forms may be written upon at all places without the operator's hand resting thereon, thus preventing smudging of the carbon copies of the "form." It also has the advantage of permitting the use of carbon sheet 41 which are only half the width of the usual carbon sheet for the same length "form." Because of this arrangement, it 90 is ensured that the carbon sheet is fully used. Ordinarily, since only about one-half of a "form" is used, only one-half of the carbon sheet is used, and consequently the unused part of the carbon sheet must be 95 discarded with the used, resulting in considerable loss. The present invention as above set forth overcomes this disadvantage. The carbon sheets 41 are supported in a frame 42 at the side of the machine in the 100 usual manner.

When the parts are in position shown in Figs. 1 and 2 and the first half of the "form" has been written upon, and it is desired to move the entire other part to writing position, the platen 27, which carried the pin-wheels 30, is pushed forwardly by means of a handle 43 at its end and this causes the portion of the platen 27 and webs 26 carried thereby which was previously located beneath the hand rest 21, to be moved into the writing zone. This advance of the webs to the writing zone is not attended by a rotation of the pin-wheels 30 but these are held against their tendency toward retrograde rotation by a spring urge back-check pawl 44 pivotally carried by a bracket 45 mounted on the pin-wheel frame 33 and engaging a ratchet wheel 46 secured to the pin-wheel shaft 31, the pins 29 merely act- 115

ing to hold the webs on the platen to move therewith.

At this point it should be noted that the pins of each pin-wheel pass through a slot 47 provided in the top 35 of the pin-wheel frame 33 the forward portions of which act to strip the webs from the pins 29 as they are moved across the slots by the pins. The webs are held in engagement with the pins 29 by slotted blocks 48 having depending portions 49 secured to the side plates 34 of the pin-wheel frame. The pins passing through said slots while the webs are held to the top plate 35 by the parts of the blocks 48 adjacent the slots. The blocks 48 are connected together by the handle 43 which has supporting arms 50 secured to the blocks and a knife bar 51 secured at its ends to the block and against which knife bar the "forms" are severed from each other after the delivery thereof by the pin-wheels.

After the second half of the "form" has been written upon it is desired to deliver the "form" past the knife bar 51 so that it can be severed from the next "form" and used. According to this invention, in the form now being described, this is accomplished by a simple backward movement returning the platen to its normal position. Of course, if the second half of the form was not needed, then the first step in the operation of delivering the "form" is to push the handle 43 forwardly and the latter is then immediately returned to normal position by a pulling action. During the return movement of the parts, a full "form" length is fed past the pin-wheels and this is accomplished by means of the pinions 38 which mesh with the racks 40 and also mesh with pinions 52 mounted on the pin-wheel shaft 31 to rotate the latter in a forward direction only, by means of a one-way clutch 53. The ratio of the gearing 40, 38, 52 is such that for the rearward travel of the pinion 38 over a distance equal to the length of one-half a "form" the peripheral distance traveled by the pin-wheels with relation to the platen will equal one "form" length.

It should be understood that this advancement of the webs refers merely to the delivery of the webs past the knife bar 51 and not the feeding of the webs from the rolls 24, for, according to this invention, the webs are fed from the rolls independently, that is, without any of the work being done by the rotation of the pin-wheels. This is accomplished by feeding one "form" length from the rolls when the platen and pin-wheels are moved forwardly. One-half of a "form" length is fed by the actual forward movement of the platen and pin-wheels, since the webs pass over rollers 54 at the rear of the frame 20. The other half "form" length is fed at the same time by means of a bail 55 supporting rollers 56 engaging the

webs between the stationary rollers 54 and other stationary rollers 57 located beneath the rollers 54, the webs passing from their rolls 24 over the rollers 57 then over the rollers 56 and finally over the rollers 54 to the platen 27. When the platen is moved forwardly, the bail 55 is also moved forwardly to feed one-half form length from the rolls 24 by its movement; and, its movement is effected by means of a slotted link 58 pivotally carried at 59 by the platen frame arms 35 and engaging a pin 60 secured to the bail 55. During the forward movement of the platen, the end of the slot in the link 58 engages the pin 60 and draws the bail forwardly. The movements of the bail are limited by a pair of pins 61 adjustably mounted in the side plates 20. When the platen is returned, the slack in the free stretch of the webs is taken up by the rotation of the pin-wheels and return of the bail 55 is positively effected by the link 58 in the same manner as it is moved forwardly. It will thus be seen, that during the delivery of the webs there is no drag produced thereon by the rolls 24 and that the only work which the pin-wheels need do is to either hold the webs during feeding-off of the webs from the rolls or to advance the fed-off webs over the platen during the delivery of the forms after the writing has been finished.

In case there is only a few lines to be written upon, or in case the operator prefers to advance the "form" line-by-line during the writing of the second half of the "form", the platen may be advanced by line space mechanism provided for the purpose. In the form shown in Fig. 1, this line space mechanism comprises a single element consisting of a handle 62 located outside of the side plate 20 and an arm 63 located inside the plate 20 and secured to the handle by means of a rod 64 passing through a slot 65 in the side plate. The upper portion of the arm 63 is provided with a projection 66 adapted to engage ratchet teeth 67 carried by the platen 27. The arm 63 is held with its projection 66 beneath the plane of the bottoms of the teeth 67 by means of a spring 68 which also tends to return the arm and handle to normal position after having been operated. In operation, when the handle is pushed forwardly the projection 66 engages one of the ratchet teeth and advances the platen one line-space at which time the movement of the arm 63 is limited by engagement with a stop 69. In returning it is necessary for the projection 66 to pass one of the teeth 67 and to permit this the slot 65 is elongated so as to allow a bodily descending movement of the handle and arm. This descending movement is opposed by a spring 70 which tends to hold the parts elevated and which assists the spring 68 in returning and holding the parts in normal position.

In Fig. 4 there is shown a modification of this line-space mechanism. In this form the handle and arm are not mounted for bodily ascending and descending movement. Instead, the arm 63 is provided with a pivoted pawl 66^a adapted to be urged by a spring 68^a into engagement with the ratchet teeth 67. In normal position, however, the pawl is maintained out of range of the teeth 67 by means of an abutment 71 engaging a cam surface 72 on the pawl. When the handle is operated, (that is, is moved forwardly), the cam surface 72 moves away from the abutment 71 and the spring 68^a moves the pawl into engagement with the teeth 67. The continued movement of the handle and pawl advances the platen. During the return movements of the parts, the pawl merely passes idly over the ratchet teeth. The forward movement of the parts is limited by means of a stop 72 which is adjustable in a slot 73 for the purpose of permitting the movement of the platen to be varied to meet varying conditions.

As shown in Fig. 7, the top plate 21 is extended at 74 to overlie the portions of the webs which are perforated so that the writing zone exposes only the portion of the "form" which is to be written upon.

The front plate 23, in the form of the invention above described, is left open directly in front of the path of the pin-wheels so that the latter may move outwardly of the frame when the platen is moved to the position shown in Figs. 6 and 7.

The forward and rearward positions of the platen, and consequently the extent of feeding movement incidental thereto, are controlled by means of the stops 61 which are also used to limit the movement of the bail 55 connected to the platen. The stops 61 are adapted to be adjusted in slots 75 in the side plate for the purpose of varying the extent of movement of the platen to accommodate "forms" of various lengths.

It should be understood that it also forms part of this invention to use the register above described with the normal "writing" position of parts as shown in Figs. 6 and 7, especially in cases where the items written on the "forms" usually occupy more than one-half of the space of the "forms". If this is done, the feeding operation commences with a backward movement of the platen and is completed by a forward movement returning the parts to the position shown in Figs. 6 and 7.

Another form of this invention is shown in Figs. 8 and 9 and in these figures the parts corresponding to the parts in Figs. 1 to 7 are noted by corresponding reference numerals to which have been added the prime mark.

In this form of the invention, the platen

27' is mounted to be stationary and consequently the pin-wheel frame 34' is independently mounted and has a rearwardly extending arm 75 on which the rollers 36' are mounted.

The feeding of the webs from the supply rolls is effected by the forward bodily movement of the pin-wheels which hold the latter at the front without rotating while at the rear the webs pass over rollers 54'. The movement of the pin-wheel frame to the forward limit of its motion is sufficient to feed from the rolls 24', as a consequence thereof, one full "form" length leaving nothing to be fed-off during the return stroke. When the pin-wheels are returned to normal position it is merely necessary for the pin-wheels to idly pass over the paper that has been fed and to feed this paper beneath the severing knife 51'. During the forward movement, the pin-wheels are held against retrograde movement by a back-check pawl 44' and ratchet 46', while during the return movement the pin-wheels are forced to rotate forwardly by means of a pinion 38' meshing with a rack 40', a gear 76 secured to the pinion 38', a gear 77 meshing with the gear 76, a sprocket 78 secured to the gear 77, a sprocket 52' having a one-way clutch 53' connecting it to the pin-wheels, and a chain 79 connecting the sprockets 52' and 78. The pitch diameter of the pinion 38' is the same as the diameter of the pin-wheel proper and the ratio of the gearing is 1:1 so that the rotation of the pin-wheels will just feed the paper fed-off the rolls past the knife.

Immediately in front of the knife bar 51' there is provided an auxiliary table 80 to cover an opening at the top of the register and to provide means for receiving the leading edge of the "form" as it is being fed past the knife bar.

The front of the pin-wheel frame is supported on the pinions 38' which ride on the racks 40' and to hold the pinion 38' in mesh with the rack there is provided directly above it a roller 81 riding on the track 37'.

The shaft 31' for the pin-wheels and the shaft 39' for the pinions 38' extend across the machine and serve to tie together opposite sides of the pin-wheel frame.

Having thus fully described my invention, what I claim as new and desire to secure by Letters Patent, is:

1. In an autographic register, the combination of a frame having a defined writing zone; a platen for supporting webs during writing operations; pin wheel feeding means to engage perforated portions of the webs; and means for advancing the webs relative to said writing zone by a forward, bodily movement of the pin-wheel feeding means.

2. In an autographic register, the combination of a frame having a defined writ-

ing zone; a platen for supporting webs during writing operations; pin wheel feeding means to engage perforated portions of the webs; and means for advancing the webs relative to said writing zone by a forward, non-rotating movement of the pin wheel feeding means.

3. In an autographic register, the combination of a frame having a defined writing zone; a platen for supporting webs during writing operations; pin wheel feeding means to engage perforated portions of the webs; and means for advancing the webs relative to said writing zone as an incident to a bodily movement of the pin-wheel feeding means.

4. In an autographic register, the combination of a frame having a defined writing zone; a platen for supporting webs during writing operations; pin-wheel feeding means to engage perforated portions of the webs; and means for advancing the webs relative to said writing zone as an incident to a bodily, rearward movement of the pin-wheel feeding means.

5. In an autographic register, the combination of a frame having a defined writing zone; means for supporting a plurality of rolls of webs; a platen for supporting the webs during writing operations; means for engaging the webs; and means for advancing the webs a predetermined extent as an incident to a bodily movement of the means for engaging the webs; and means for concomitantly feeding a predetermined length of the webs from the rolls independently of said web engaging means.

6. In an autographic register, the combination of a frame; a platen supported by the frame for supporting webs during writing operations; and pin-wheel feeding means mounted for traveling movement relative to said frame.

7. In an autographic register, the combination of a frame; a platen for supporting webs during writing operations; and means in continuous control of said webs and movable relative thereto while so in control for advancing the webs when moved bodily parallel to the path of movement of the webs.

8. In an autographic register, the combination of a frame having a defined writing zone; a platen for supporting webs during a writing operation; pin-wheels for engaging perforations in said webs; means for imparting to said pin-wheels a bodily movement to advance the webs relative to the writing zone; and means for holding the pin-wheels against rotation during said bodily movement of the pin-wheels.

9. In an autographic register, the combination of a frame having a defined writing zone; a platen for supporting webs during writing operations; pin-wheels for engaging perforations in the webs; means for

imparting to said pin-wheels a bodily movement to advance the webs relative to the writing zone; and means for compelling rotation of the pin-wheels during said bodily movement.

10. In an autographic register, the combination of a frame having a defined writing zone; a platen for supporting webs during writing operations; pin-wheels for engaging perforations in said webs; means for imparting to said pin-wheels a bodily movement to advance the webs relative to the writing zone; means for holding the pin-wheels against rotation during said bodily movement; and means for compelling rotation of the pin-wheels during companion bodily movement of the pin-wheels.

11. In an autographic register, the combination of a frame having a defined writing zone; a platen for supporting webs during writing operations; pin-wheels for engaging perforations in said work; means for imparting to said pin-wheels a forward bodily movement of the pin-wheels for advancing the work relative to the writing zone; means for holding the pin-wheels against rotation during said forward movement of said pin-wheels; and means for compelling rotation of the pin-wheels as an incident to the return movement of the pin-wheels.

12. In an autographic register, the combination of a defined writing zone; a platen for supporting a web in the form of a succession of form lengths; and web engaging means for advancing the web a portion of a form length as an incident to a predeterminedly limited actuation thereof.

13. In an autographic register, the combination of a frame having a defined writing zone; a platen for supporting a web in the form of a succession of form lengths; web engaging means for advancing the web relative to said writing zone a portion of a form length as an incident to a predeterminedly limited actuation thereof; and means for advancing the web the remainder of the form length upon a subsequent actuation of the advancing means.

14. In an autographic register, the combination of a frame having a defined writing zone; a platen for supporting a web in the form of a succession of form lengths; pin-wheel feeding means for advancing the web relative to the writing zone a portion of a form length as an incident to a predeterminedly limited, forward bodily movement of the pin-wheels; means for holding the pin-wheels against rotation during said forward movement of the pin-wheels; and means for compelling a web advancing rotation of the pin-wheels during the return movement of the pin-wheels to advance the remainder of the form length relative to the writing zone and to move the pin-wheels

one complete form length relative to the web.

15. In an autographic register, the combination with a frame having a definite writing opening, of a web supporting platen located beneath said opening supported by the frame; and pin-wheels engaging perforations in said webs for feeding the latter over said platen as an incident to a bodily movement of the pin-wheels in a counter-direction.

16. In an autographic register, the combination of a frame having a defined writing zone; a platen for supporting webs during writing operations; and feeding means for the webs comprising pin-wheels for engaging perforations in the webs, a slide mounted in the frame and manually operable, and means for causing the pin-wheel to advance the work relative to said writing zone as an incident to the manually operation of said slide.

17. In an autographic register, the combination of a platen; means for supporting the platen for traveling movement in line-space direction; and means for moving said platen step-by-step relative to said writing opening.

18. In an autographic register, the combination of a frame having a defined writing opening; a platen located beneath said opening; and means for advancing the platen step-by-step relative to said opening.

19. In an autographic register, the combination of a frame having a defined writing opening; a platen located beneath said opening; and means for advancing the webs step-by-step relative to said writing opening.

20. In an autographic register, the combination of a frame having a defined writing zone; a platen mounted for traveling movement relative to said writing zone; ratchet teeth on said platen; a pawl; and operating means therefor, said pawl upon each operating movement engaging the ratchet teeth and moving the platen one line-space increment.

21. In an autographic register, the combination of a frame having a defined writing zone; a platen for supporting webs to be written upon; means on said frame for supporting manifolding material in extended position across the writing zone and between the webs; and means for advancing the webs step-by-step relative to the manifolding material and the writing zone.

22. In an autographic register, a platen adapted to support a plurality of sheets thereon beneath a writing opening, and pin wheels adapted to be inserted into perforations in said sheets to align said sheets and hold them in position, said means being carried by the platen.

23. In an autographic register, a platen

adapted to support a plurality of sheets thereon beneath a writing opening, means adapted to be inserted into perforations in said sheets to align said sheets and hold them in position, said means being carried by the platen, and adapted to be moved with said platen bodily in one direction and means to retain said aligning and positioning means when the platen is moved in another direction to eject a predetermined amount of said sheets.

24. In an autographic register, a platen adapted to support a plurality of sheets thereon beneath a writing opening, means adapted to be inserted into perforations in said sheets to align said sheets and hold them in position, said means being carried by the platen, and adapted to be moved with said platen bodily in one direction, means to retain said aligning and positioning means when the platen is moved in another direction to eject a predetermined amount of said sheets, and means to move said platen step by step when desired.

25. In an autographic register, a plurality of rolls of paper carried therein, a movable platen adapted to serve as a writing table upon which the several sheets from the rolls of paper are superimposed, means carried by said platen engaging with the respective strips of paper for unwinding said rolls a predetermined length when the platen moves in one direction, means carried by the platen to align and hold stationary said sheets when the unwinding operation is taking place, and adapted to eject said sheets from the platen the length they were previously unwound upon the movement of the platen in the other direction whereby predetermined lengths of the sheets are alternately unrolled from the rolls and ejected from the platen while the tension on the sheets is retained constant at all times and their alignment is maintained.

26. In an autographic register adapted to carry a plurality of rolls of paper, a reciprocating platen upon which the sheets from said rolls are superimposed, said sheets having marginal perforations, pin-wheels carried by said platen adapted to have their pins engage with said perforations, means to prevent said pin-wheels from rotating in one direction, means to actuate said pin-wheels when moving in another direction whereby when the platen is bodily moved in one direction the sheets of paper will be drawn in that direction a predetermined distance, and when the platen moves in the other direction the rotating pin wheels will eject the sheets the predetermined distance desired.

27. In an autographic register adapted to carry a plurality of rolls of paper, a reciprocating platen upon which the sheets from said rolls are superimposed, said sheets having marginal perforations, pin wheels carried by said platen adapted to have their

pins engage with said perforations, means to prevent said pin wheels from rotating in one direction, means to actuate said pin wheels when moving in another direction whereby when the platen is bodily moved in one direction the sheets of paper will be drawn in that direction a predetermined distance, and when the platen moves in the other direction the rotating pin-wheels will 10 eject the sheets the predetermined distance desired, and independent means to move said platen step by step in one direction with its pin-wheels.

28. In an autographic register, a plurality 15 of rolls of paper carried therein, a movable platen adapted to serve as a writing table upon which the several sheets from the rolls of paper are superimposed, means carried by said platen engaging with the respective 20 strips of paper for unwinding said rolls a predetermined length when the platen moves in one direction, means carried by the platen to align and hold stationary said sheets when the unwinding operation is taking place, and 25 adapted to eject said sheets from the platen the length they were previously unwound upon the movement of the platen in the other direction whereby predetermined lengths of the sheets are alternately unrolled 30 from the rolls and ejected from the platen while the tension on the sheets is retained constant at all times and their alignment is maintained and a bail pivotally mounted on said register having its free end engaging 35 with said sheets adapted to be actuated by the reciprocating platen to which it is connected, the parts being arranged so that when the platen is being moved in one direction with the pin-wheels they will be stationary to hold the paper and the paper will

be unrolled by the bail of predetermined length and upon the return of the platen the pin-wheels will eject the surplus of paper thus unwound so as to present a fresh writing surface of paper on the platen.

45

29. In an autographic register, a plurality of rolls of paper carried therein having their sheets superimposed upon a reciprocating platen, a reciprocating platen and handle to actuate it, means on said register for guiding said platen in its reciprocating movement, a pair of pin-wheels suspended from said platen having their pins engaging with the marginal perforations in the margins of the paper, intermediate gearing connecting said pin-wheels with a rack on said register and a clutch, said gears being adapted to actuate the pin-wheels in one direction only through the agency of said clutch.

55

30. In an autographic register, a plurality of rolls of paper carried therein having their sheets superimposed upon a reciprocating platen, a reciprocating platen and handle to actuate it, means on said register for guiding said platen in its reciprocating movement, a pair of pin-wheels suspended from said platen having their pins engaging with the marginal perforations in the margins of the paper, intermediate gearing connecting said pin wheels with a rack on said register 60 and a clutch said gears being adapted to actuate the pin wheels in one direction only through the agency of said clutch, said platen having cutaway portions through which the pins project successively for engaging with the perforations in the paper and a knife member carried by said platen 65 for severing the sheets of paper.

75

In testimony whereof, I affix my signature.
ARTHUR A. JOHNSON.
